ESCAPE HATCH

Nathan Heffner, Brooklyn, and Simon O. Heffner,
Great Neck, N. Y.

Application August 12, 1943, Serial No. 498,298

6 Claims. (Cl. 292—53)

This invention relates generally to hatches and more particularly to quick operating hatches especially useful for the escape of seamen from the quarters in which they may become accidentally entrapped.

As is well known in the nautical field, when, owing to accident or attack in war, a portion of the ship becomes flooded or afire, so that the normal exit from a room or through a bulkhead is obstructed, it is desirable that some additional exit or exits be provided, such exits being located in opposite walls or bulkheads, or communicating with different companionways or passages from those which are effected by the obstructing conditions. Where the deck or outermost side wall portions of the hull are adjacent or adjoining, it is desirable that these auxiliary exits communicate therewith or lead directly out thereon.

As a result of concussion, shock, water, or noxious gases, caused by combustion or otherwise, the occupants of the particular chamber, room, or hold, may be dazed, partially asphyxiated, or otherwise physically incapacitated, so that it is desirable that the escape hatches provided be easily operated and be of such a simple nature in the operation thereof that they may be successfully opened under the most adverse conditions.

It is therefore among the principal objects of the present invention to provide novel and highly useful escape hatch constructions which may be prefabricated as a unit and installed in any desired wall or bulkhead of a ship merely by cutting the requisite sized opening in the wall or bulkhead and securing the escape hatch in place.

Another object herein lies in the provision of a structure of the class described which, while of relatively light weight, possesses adequate strength so that the same may, when desired, be positioned upon the outer hull or deck of the ship upon which it is installed.

Another object herein lies in the provision of escape hatch structure in which the opening thereof may be substantially instantaneously performed, so as not to hinder the escape of the occupant or occupants under extremely hazardous conditions.

A feature of the present invention lies in the fact that the escape hatch may be operated by a simple pulling or pushing operation, as the case may be, and in which the operation thereof is made so obvious to the user that he may successfully accomplish his escape even though he may be in a below-normal physical condition.

In accordance with the present invention, structure is disclosed wherein, where the escape hatch has the outer portion thereof accessible to a companionway, passage, or other area likely to be occupied or reached by other persons than the one or ones trapped, the same may be actuated from the outside thereof.

A feature of the present invention permits the same to be used under circumstances where the wall, within which the escape hatch is positioned, needs be water-tight. In the use of the present invention, a water-tight connection between the cover plate of the escape hatch and the surrounding portions may be obtained in a quick and easy manner.

These objects and other incidental ends and advantages will more fully appear in the progress of this disclosure and be pointed out in the appended claims.

20 In the drawings in which similar reference characters designate corresponding parts throughout the several views of each embodiment:

Figure 1 is a fragmentary front elevational view of a first embodiment of the invention.

Figure 2 is a vertical sectional view as seen from the plane 2—2 on Figure 1.

Figure 3 is a vertical sectional view through a bulkhead showing the first embodiment of the invention as installed in a generally vertical position.

Figure 4 is a fragmentary sectional view through a portion of deck showing the first embodiment of the invention in a generally horizontal installation.

Figure 5 is an enlarged fragmentary elevational view partly in section showing the details of the stuffing box of the first embodiment of the invention.

40 Figure 6 is a fragmentary vertical sectional view of a second embodiment of the invention.

Figure 7 is a fragmentary front elevational view of a third embodiment of the invention.

Figure 8 is a vertical sectional view as seen from the plane 8—8 on Figure 7.

Figure 9 is a vertical sectional view corresponding to Figure 2 but showing certain of the parts in an altered position thereof.

Figure 10 is an enlarged fragmentary sectional view of the right hand portion of Figure 10 but shows certain of the parts in an altered position thereof.

Turning now to the first embodiment of the invention illustrated in Figures 1—5, inclusive, the escape hatch, generally indicated by numeral 10,

comprises broadly a hatch cover element 11; a coaming element 12; and latching, compression, and opening mechanism, generally indicated by reference character 13.

The coaming element may be of any suitable general size, but the effective internal diameter thereof is preferably sufficient to allow the passage therethrough of a person aboard ship, or other structure upon which the hatch 10 is used. We have found that the length of any of the top, bottom and side walls of the coaming element 12 may be varied between eighteen and twenty-four inches with satisfactory exit. The top, bottom and side walls of the coaming element 12 are indicated by numerals 14, 15, 16 and 17, respectively. The coaming element is preferably composed of sheet steel. Secured to the inner surfaces of the opposed side walls 16 and 17 are the latching lugs 18-21, inclusive. These lugs may be in the form of steel blocks, and may be integrated with the inner surface of said coaming element in any suitable manner, as for example, by welding. The front or active surfaces 22-25, on the lugs 18-21, respectively, are preferably flat and in a common plane. The outer surfaces of the walls 14-17, are provided with a mounting flange 26 which may suitably be secured thereto, for example, by welding. As best seen in Figure 2, the position of the flange 26 determines the ultimate amount of projection of the cover element 11 with relation to the deck of bulkhead 27. Where the front surface 28 of the flange 26 is in contact with a wood deck or bulkhead, the same may be secured thereto in watertight connection by using a canvas and red lead gasket (not shown) between the surface 28 and the top surface of the deck or rear surface of the bulkhead, as the case may be, and suitable bolts. Where the flange 26 is in contact with a steel bulkhead, said flange may be welded to the bulkhead.

It may thus be seen that in order to mount the coaming element 12 it is only necessary to cut an orifice of corresponding size in the deck or bulkhead upon which the coaming element is to be mounted and to secure the same in place by the engagement of the outer surfaces of the top, bottom and side walls of the coaming with the bordering edges of the said orifice; and by securing the flange radially extending from the outer surfaces of said walls to the deck or bulkhead, as the case may be.

The hatch cover element 11 is preferably composed of sheet steel and includes an outer forwardly extending peripheral flange 29. The flange 29 may be integral with the body 30 and may be formed by bending the edge of said body through ninety degrees. The cover element 11 is provided with an annular rim gasket 31 which may be composed of any suitable material adapted to promote a water-tight seal against the rear edge 32 of the coaming element 12 when said cover element 11 is uncompressed. We have found that the gasket 31 may be composed of impregnated flax or rubber. The gasket 31 is maintained in place by a gasket retainer 33. The retainer 33 may be in the form of an annular band positioned so as to be spaced and substantially parallel to the inner surfaces of the flange 29. The retainer 33 may be secured to the forward surface of the body 30 in any suitable manner, as for example, by welding and is preferably slightly angularly disposed with relation to the flange 29 so as to converge forwardly toward the flange 29. This construction forms a

channel having a narrowed mouth or annular opening within which the gasket 31 is maintained by compression. Thus, the rim gasket 31 as maintained in position between the flange 29 and the retainer 33 is under a primary compression and when the cover element 11 is in the closed, or coaming-engaged position thereof, said gasket 31 is subjected to a secondary compression, as will more fully appear hereinafter.

10 The hatch cover element 11 may be hingedly connected to the coaming element 12, for example by means of the hinges 34 and 35. Since the hinges 34 and 35 are substantially identical, a detailed description of one will suffice for both. 15 As best seen in Figure 2 of the accompanying drawings, the hinge 34 includes a pair of relatively stationary members 36 and a relatively movable member 37. The members 36 are secured in any suitable manner to the rear surface 20 38 of mounting flange 26, as for example, by welding. The member 37 is secured to the rear surface 39 of the body 30 in any suitable manner, as for example, by welding and is pivotally connected to the members 36 by means of a double-headed pin 40. The pin 40 penetrates a round orifice in the member 37 and elongated orifices 41 in the members 36. The elongated orifices 41 permit the hatch cover element 11 to shift in position slightly so that the forward surface of the 25 gasket 31 may properly line-up with the rear edge 32 of the coaming element 12.

30 The body 30 of the hatch cover element 11 is provided with a stuffing box 42 which is preferably secured thereto by mounting the same in an orifice in said body and welding or brazing the outer cylinder 43 thereto. This construction is shown in detail in Figure 5. The cylinder 43 is provided in the forward portion thereof with a bushing 44 preferably composed of brass and having an external diameter substantially equal to the internal diameter of the cylinder 43, and having an internal diameter substantially equal to the diameter of the rod 45. The rear or outer end of the cylinder 43 has a cap 46 in threaded engagement therewith. Disposed within the cap 46 and the cylinder 43 is a gland 47 preferably composed of brass. A flax or other suitable packing 48 is positioned about the rod 45, within the cylinder 43 and between the bushing 44 and the gland 47. The compression upon the packing 48 sufficient to maintain the rod 45 in slidably watertight connection with the stuffing box 42 is obtained by rotating the cap 46.

35 The latching, compression, and opening mechanism generally indicated by reference character 13, includes a pair of latching members 49 and 50 which are fixedly interconnected in direct spaced and parallel arrangement by the tie-bars 51 and 52. The latching members at the outer 40 extremities thereof are provided with end surfaces 53, 54, 55, and 56 which are adapted to engage with the latching lugs 18, 19, 20, and 21, respectively.

45 We have found that adequate strength of the parts, and a reduction in weight is obtained by forming the latching members of tubing, so that these members are hollow throughout the length thereof. The ends of the tie-bars 51 and 52 are preferably rigidly secured to the opposed surfaces of the latching members 49 and 50 in any suitable manner, as for example, by welding. The thus integrated structure of the latching members 49 and 50 and the tie-bars 51 and 52, hereinafter referred to as the latching element 57, is shiftable vertically, as shown in Figures 1, 2, and 9,

in an arcuate path of travel with the element 57 being positionable in a series of planes generally parallel to the body 39 or the rear edge 32 of the coaming element 12.

The links 59, 60, 58, and 61 are pivotally mounted at the rear ends thereof upon brackets generally indicated by numeral 62, forwardly projecting from the front surface of the body 30 and suitably secured thereto in any manner, as for example by welding. Said last mentioned links are pivotally connected at the forward ends thereof to the tie-bars 51 and 52, adjacent the extremities thereof. The upper ends of the tie-bars 51 and 52 are provided with extensions 63 and 64 which serve to trunnion the pins 65 and 66 so that a freely operating pivotal joint is provided. The lower ends of the tie-bars 51 and 52 are provided with extensions 67 and 68 which serve to trunnion the pins 69 and 70 so that a freely operating pivotal joint is provided. A pair of bell crank levers 71 and 72 are loosely pivotally secured at the lower rear ends thereof to a pair of brackets, generally indicated by numeral 73, and at the upper ends thereof are interconnected by a bar 14. The levers 71 and 72 are generally L shaped and the arms thereof preferably form an angle of slightly more than ninety degrees. The levers 71 and 72 at the intersection of the arms thereof are loosely pivotally connected to the tie-bars 51 and 52 by the pins 75 and 76. The inner ends of the pins 75 and 76 are trunnioned in the upper ends of the extensions 67 and 68. The loose pivotal connection at the pins 75 and 76 and at the lower rear ends of the levers 71 and 72 is to compensate for the difference in arcuate travel of the forward ends of the links 58-61 and the short arms of said levers. The extensions 67 and 68 connect with the tie-bars 51 and 52 by the stays 77 and 78. As seen in Fig. 9 rearward movement of bar 74 causes levers 71 and 72 to swing about the axis of the pivotal connection to the bracket 72 and elevate the latching element. The bar 74 may have secured to the forward surface thereof a push plate 79 and to permit operation of the escape hatch 10 by even the uninitiated, the plate 79 may carry suitable indicia, such as the word "Push" and in order to permit the same to be legible even under adverse lighting conditions, said indicia 80 may be in the form of luminous paint. Since the axis of rotation of the hatch cover element 11 as a unit, is about the pins 40, the pressure upon the plate 79 which is sufficient to disengage the latching element 57 from the lugs 53-56, inclusive, is ample to push the hatch cover element 11 so that the center of gravity thereof is rearwardly of a vertical plane passing through the pins 40. The hatch cover element 11 will now swing downwardly and rearwardly by the action of gravity so as to clear the passage through the coaming element 12. The plate 79 is provided with a central orifice 81 adapted to receive the eye 82 at the forward end of the rod 45 which encircles the bar 74. The eye 82 has an elongated orifice 83 so that the bar 74 may vertically reciprocate within said orifice 83. The rear end of the rod 45 is provided with a pivotally mounted ring or other suitable operating handle 84. Thus where it is desired to open the hatch cover plate 11 from a position rearwardly thereof, it is necessary only to manually pull the handle 84 which shifts the rod 45 rearwardly and correspondingly moves the bar 74.

In order to close the hatch 10 it is only necessary to re-seat it with the edge 32 of the coaming

12 in contact with the gasket 31 and to move the bar 74 in a counter-clockwise direction as viewed in Figure 9 which will bring the parts to the position shown in Figure 2. To place the gasket

31 under greater compression or to compensate for wear in said gasket, only further counter-clockwise movement of the bar 74 (away from the body 30) is necessary because when the links 58 and 59 (in Figure 2) drop down from their horizontal perpendicular positions they pull the members 49 and 50 toward the body 30.

Turning now to the second embodiment of the invention illustrated in Figure 6, for the purpose of avoiding needless repetition, parts corresponding to the first embodiment are given the same reference character with the addition of the numeral "1" as a prefix. In this embodiment it will be seen that the hatch cover plate 111 is adapted for mounting flush with the deck for use as a water-tight deck hatch. For this purpose the coaming element 112 is mounted in a depressed position and the mounting flange 126 is of double angled construction. The outermost portion of the flange 126 is secured in any suitable manner to an annular ledge 185, which may be suitably secured to the under-surface of the deck 186 in any suitable manner, as for example, by welding. By virtue of this construction the body 130 of the cover element 111 is substantially planar with the exception of the well 187. The flange 129 may be constructed similarly to the gasket retainer 133 and may be secured to the under-surface of the body 130 in any suitable manner. The convergence toward each other of the flange 129 and the retainer 133 serve to properly secure the gasket 131 in operative position.

It is preferable that in this construction no hinges be used, though, of course, where desired, they may be incorporated, so that an upward pull on the handle 184 or an upward push on the bar 174 or plate 179 will disengage the latching element 157 so that the cover element 111 may be lifted or pushed clear of the opening through the coaming element 112.

In Figure 10 the position of link 159, the member 50 and the extension 67 is shown when the gasket 131 is under extreme pressure, a position taken when the bar 174 is pulled down in a counterclockwise direction as viewed in Figure 6.

Turning now to the third embodiment of the invention illustrated in Figures 7 and 8, here again for the purpose of avoiding needless repetition, parts corresponding to the first embodiment of the invention are given the same reference character with the addition of the numeral "2" as a prefix.

As shown in Figure 7, the latching members 249 and 250 are vertically arranged and associated structure is correspondingly positioned. This embodiment differs from the first embodiment principally in the opening of the hatch being accomplished by pulling on the bar 274 and in the elimination of the means for actuating the latching, compression, and opening mechanism from the rear surface 239 of the body 230.

Thus as shown in Figures 3 and 4, the present escape hatches may be used on horizontal surfaces such as decks, or on vertical surfaces such as bulkheads. The escape hatches may be repetitively operated for test and trial purposes since the re-seating of the hatch cover element to its original closed position requires merely the replacement of the cover element so that the gasket seats against the rear or outer rim or edge of the coaming element and the movement of the

operating handle on one side of the cover plate or the other, as the case may be, to its original position or beyond to fully compress the gasket and obtain a leak proof seal thereat. By virtue of the compound leverage effect, the consequent mechanical advantage obtained, provides for sufficient pressure even when only manual pressure or pull is exerted on the particular operating handle.

It may thus be seen that we have provided a novel and useful escape hatch construction which is simple and foolproof in operation and is capable of satisfactory performance over long periods of time and under adverse conditions. The combination construction may be fabricated as a unit and may be installed aboard ship by merely cutting the requisite sized opening to receive the coaming element and suitably securing the mounting flange in connection with the border of said opening. Relatively little physical strength is required to open or close the hatch and to actuate the latching mechanism. This feature is especially advantageous since it may be necessary to actuate the closure and to open the same under extremely adverse conditions. In those embodiments of our invention in which the cover plate may be opened from either the front or rear surfaces thereof, it becomes possible to reach entrapped men, who are, by reason of injury, unable to reach or actuate the escape hatch, and to remove them through the hatch after the same has been opened.

We wish it to be understood that we do not desire to be limited to the exact details of construction shown and described, for obvious modifications will occur to a person skilled in the art.

We claim:

1. In an escape hatch including a coaming element and a hatch cover element; latching means disposed within the coaming element for detachably attaching said hatch cover element to said coaming element; said means including a lug on the coaming element and a latching member on the hatch cover element, said member being movably supported by a pair of links each having two ends, one end of each of said links being pivotally connected to said latching member and the remaining end of each of said links being pivotally connected to the hatch cover element.

2. For use with an escape hatch including a coaming element; a hatch cover element; latching means disposed within the coaming element for detachably attaching said cover element to said coaming element; said means including a lug on the coaming element and a latching member on the hatch cover element; said latching member having an end surface engageable with said lug and facing the said cover element, and

being movably supported by a pair of links, each having two ends, one end of each of said links being pivotally connected to said latching member and the remaining end of each of said links being pivotally connected to the cover element; and second means to prevent rotation of said latching member about itself whereby said end surface may always engage said lug.

3. For use with an escape hatch a coaming element having a passage and a hatch cover element adapted in a closed position thereof to obstruct said passage and in an open position thereof to clear said passage, latching means comprising: a plurality of stationary lugs secured to the coaming element; a latching element composed of a plurality of latching members in fixed position with relation to each other and each being disposed adjacent a corresponding one of said lugs; a plurality of links spaced and parallel with respect to each other, each of said links being pivotally connected at one end thereof to said hatch cover element and at the other end thereof to said latching element, whereby the latching element is capable of arcuate movement simultaneously as a unit toward and away from said hatch cover element and laterally of said hatch cover element; said lugs and latching members being so positioned with respect to each other that when the hatch cover element and the coaming element are in a closed position the latching members begin to engage the lugs when the latching members are most distant from the hatch cover element.

4. Structure as claimed in claim 3 including means to move the latching element comprising a substantially L shaped lever having one arm thereof pivotally connected to the hatch cover element and the apex of said lever connected to the latching element.

5. Structure as claimed in claim 3 including means to move the latching element comprising a substantially L shaped lever having one arm thereof pivotally connected to the hatch cover element, and an extension pivotally connected to the apex of the L shaped lever and pivotally connected to the latching element.

6. An escape hatch construction as claimed in claim 3 including means to move the latching element comprising a substantially L shaped lever having one arm thereof pivotally connected to the hatch cover element, and an extension pivotally connected to the apex of the L shaped lever and pivotally connected to the latching element; and a reciprocal actuating rod slidably penetrating the hatch cover element and slidably connected to the other arm of the L shaped lever.

NATHAN HEFFNER.
